CLAIM

The ornamental design of a portion of a floor care appliance, as shown and described.

DESCRIPTION

FIG. 1 is a perspective view of a portion of a floor care appliance showing our new design;

FIG. 2 is a front view thereof;

FIG. 3 is a left side view thereof; and,

FIG. 4 is a right side view thereof.

The details shown in broken lines in all views are for illustrative purposes only and form no part of the claimed design.
